UNITED STATES PATENT OFFICE.

EDWARD R. MILLS AND CHARLES A. CONN, OF PITTSBURG, PENNSYLVANIA, ASSIGNORS TO
WILLIAM S. ELLIOTT, OF PITTSBURG, PENNSYLVANIA.

ROTARY MOTOR.

No. 814,155.

Specification of Letters Patent.

Patented March 2, 1909.

Application filed February 10, 1908. Serial No. 415,041.

To all whom it may concern:

Be it known that we, EDWARD R. MILLS and CHARLES A. CONN, both of Pittsburg, Allegheny county, Pennsylvania, have invented a new and useful Improvement in Rotary Motors, of which the following is a full, clear, and exact description, reference being had to the accompanying drawings, forming part of this specification, in which—

Figure 1 is a longitudinal section of a motor embodying our invention; Fig. 2 is a section on the line II—II of Fig. 1; Figs. 3 and 4 are detail views of the partition or head which parts the two cylinders; and Fig. 5 is a detail view showing a modified construction of piston.

Our invention has relation to the class of rotary motors, and is designed to provide a simple, compact and efficient motor, which will be free from dead points, and which can be used for a variety of purposes.

Our invention consists broadly in a rotary motor having two or more cylinders arranged in tandem, with a piston shaft extending through and common to both cylinders and carrying a piston blade in each cylinder, the blades in the different cylinders being at different angles to the axis of the shaft, together with means for supplying actuating fluid, such as air, to both cylinders under pressure.

The precise nature of our invention will be best understood by reference to the accompanying drawings, in which we have shown one embodiment of our invention, and which will now be described, it being premised, however, that the invention is susceptible to various other embodiments, and that various changes may be made in the details of construction and arrangement by those skilled in the art without departing from the spirit and scope of our invention as defined in the appended claims.

In these drawings, the numeral 2 designates a cylinder, which is seated at its ends in and secured between the end heads 3 and 4, preferably by means of long tension screws 5, which extend through the head 4 and through the walls of the cylinder 2 into threaded engagement with the head 3. These screws form a convenient and simple means for securing the parts together, and which enable them to be readily removed when necessary. The cylinder 2 has formed in the

wall thereof a longitudinally extending admission port 6, which at its rear end opens into an admission chamber 7 in the rear head 3, said head being provided with a screw threaded socket 8, or with other suitable means, for the connection therewith of a motive fluid supply pipe.

The cylinder 2 is preferably formed in two sections, and secured between the meeting ends of these sections and dividing the interior of the cylinder into two separate chambers, is a ring 9, which is shown in detail in Fig. 3. This ring is formed with the slots 10 and 11, the slot 10 forming a part of the admission port 6, and the slot 11 forming part of an exhaust port 12, which is also formed in the walls of the cylinder sections. This port 12 is closed at its rear end, but extends at its forward end through the forward head 4 to the front face thereof where it discharges, although the discharge may be at any other convenient point. The ring 9 is also formed with the peripheral seats or openings 13 for the tension screws 5.

The admission port 6 is connected with the piston chambers of each of the cylinder sections by a plurality of cross-ports 14, and the exhaust port 12 is also connected with the interior of both cylinder sections by a plurality of cross-ports 15.

16 designates a piston shaft, which extends through and is common to both cylinders. This shaft is preferably journaled in removable bushings 16^a seated in the respective heads. Said shaft carries a radially movable piston blade 17 in one of the cylinder chambers, and a second and similar blade 18 in the other cylinder chamber, these two blades being shown as at right angles to each other. In the construction shown in Fig. 2, these blades are each formed of a single piece, arranged to slide radially in the shaft 16 so as to maintain contact at both edges at all times with the interior wall of the cylinder. The blades may, however, be made in sections, as shown at 19 and 20 in Fig. 5, and held in engagement at their outer edges with the inner circular walls of the cylinder by an interposed spring 21. In fact we may use any suitable construction of piston blade, as our invention is not concerned with this feature. The shaft 16 projects at its forward end beyond the end of the front head 4, and is formed with a screw-

threaded shank 22, or is provided with other suitable means, for the attachment thereto of the part to be operated by the motor.

The operation is as follows:—Air or other motive fluid under pressure is admitted to the chamber 7 and passes thence through the longitudinally extending admission head and through the cross-ports 14, into both cylinders. It is exhausted by way of the cross-ports 15 into the longitudinally extending exhaust port 12, and is discharged at the open end of said port. The operation may, however, be reversed, and the port 12 used as the admission port, and the port 6 as the exhaust port.

Owing to the fact that the two pistons are arranged at an angle to each other, it will be seen that at the time the edges of one piston are closing the admission ports 14 of its cylinder, the admission ports of the other cylinder are open. Full pressure is therefore always acting in at least one of the cylinders, and there are consequently no dead points.

The motor herein described is very simple in its construction, and is of compact form, which enables it to be used in various places where the space is limited, such for instance as in the cleaning of boiler tubes where the motor is forced through the tube to be cleaned, the cleaning tool being attached directly to the end of the piston shaft. It is, however, adapted for a variety of other purposes, and we do not limit ourselves in this respect. The motor described is particularly adapted for use with compressed air as a motive fluid, but other motive fluid may be employed, although less advantageously.

It will be obvious that instead of using two cylinders in tandem, more than two cylinders may be arranged about a common shaft, in which case the piston blades in the several cylinders will all preferably be at different angles. Various changes may also be made in the manner of forming and securing the parts.

The piston shaft 16 is preferably shouldered into the rear bushing 16^a, as shown at 23, and its inner end is provided with a thrust head or collar 24, which bears against the inner end of said bushing, thus effectually taking up the thrusts of the shaft.

We do not herein claim broadly a motor having a piston shaft common to two or

more cylinders and having piston blades arranged in the respective cylinders at different angles to each other, as such claims are made in the copending application of the present applicants and William S. Elliott, Serial No. 415,044, filed of even date here-with.

We claim—

1. In a tandem rotary engine, a pair of cylinders arranged end to end, detachable heads closing the outer ends of the cylinders, a separate partition ring situated between the abutting end of the two cylinders, a piston shaft concentric with the cylinders and their heads, an eccentrically located piston shaft in each cylinder, a piston in each piston chamber secured to the piston shaft, said pistons being at an angle with relation to each other, through inlet and exhaust passages extending through the walls of the cylinders and their separating partition, transverse ports leading from the through ports into the piston chambers, the rear cylinder head having an inlet port connecting with one of the through passages, and an exhaust in the front head connecting with the through exhaust passage, substantially as described.

2. In a tandem rotary engine, a pair of cylinders arranged end to end, detachable heads closing the outer ends of the cylinders, a separate partition ring secured in a countersunk recess in the ends of the abutting ends of the two cylinders, a piston shaft concentric with the cylinders and their heads, an eccentrically located piston chamber in each cylinder, a piston in each piston chamber secured to the piston shaft, the said pistons being at an angle with relation to each other, through inlet and exhaust passages extending through the cylinders and their separating partition, transverse ports leading from the through passages into the piston chambers, the rear cylinder head having an inlet port connecting with the through passage, and an exhaust opening in the front head connecting with the through exhaust passage, substantially as described.

In testimony whereof, we have hereunto set our hands.

EDWARD R. MILLS.
CHARLES A. CONN.
